IGNITION DISTRIBUTOR ROTOR

James L. Arthur, Anderson, Ind., assignor, by
mesne assignments, to General Motors Corpora-
tion, Detroit, Mich., a corporation of Delaware

Application February 29, 1932, Serial No. 595,743

6 Claims. (Cl. 200—19)

This invention relates to a rotor for ignition distributors for a timing distributor apparatus for an internal combustion engine.

It is an object of the present invention to pro-
vide a rotor of economical construction having a
detachable segment in order that a segment worn
out from pitting may be replaced by a new one.

Further objects and advantages of the present
invention will be apparent from the following de-
scription, reference being had to the accompany-
ing drawing wherein a preferred embodiment of
one form of the present invention is clearly shown.

In the drawing:

Figs. 1 and 2 are plan and longitudinal sectional
views of the rotor embodying the present inven-
tion.

Fig. 3 is a fragmentary sectional view on a
larger scale than Fig. 2.

The rotor includes the usual molded rotor block
20 having a recess lined with a cup-shaped mem-
ber 21 the cross sectional contour is generally cir-
cular but includes a flat 22 shown more clearly in
Fig. 1. This member 21 provides a driving con-
nection with a shaft having a similar flat. The
25 rotor 20 carries a threaded insert 23 for receiving
a screw 24 used to attach a segment 25 and a leaf
spring conductor 26 carrying a button 27 which
cooperates with the usual center contact of a dis-
tributor head, not shown. That portion of the
30 leaf spring conductor 26 which is received by the
segment 25 and the block 20 is normally bowed
as indicated by dot-and-dash lines at 28. When
the screw is tightened to secure the segment 25 to the
block 20 this portion 28 is straightened out
35 as indicated at 29. Therefore, this spring portion
29 tends to urge the segment 25 upwardly against
the head of the screw 24 thereby tending to resist
the accidental turning of the screw 24 and making
the use of a lock washer unnecessary. The turn-
40 ing of the parts 25 and 26 about the axis of the
screw is prevented by confining them between
parallel bosses 30 provided by the rotor.

The shank of the screw 24 has an unthreaded
portion 24a which is conical and is tapered so that
45 its smallest diameter is slightly smaller than the
diameter of the hole in the segment 25, and so
that its largest diameter is slightly greater than
said hole. The screw 24 is made of brass and the
segment 25 of Monel metal which is harder than
50 brass. Therefore, when the screw 24 is tightened
in the threaded insert 23, the shank 24a will bind
tightly against the cylindrical wall defining the
hole of the segment 25 and will thus prevent acci-
dental loosening of the screw 25.

55 While the form of embodiment of the present

invention as herein disclosed, constitutes a pre-
ferred form, it is to be understood that other
forms might be adopted, all coming within the
scope of the claims which follow.

What is claimed is as follows:

1. A rotor for an ignition distributor comprising
a block providing integral lugs and a tapped
hole, a metal segment supported by the block be-
tween said lugs, a screw passing through a hole
in the segment and threadedly engaging the 65
tapped hole in the block, a leaf spring conductor
having a normally bowed portion clamped between
the head of the screw and the block, the tighten-
ing of the screw in said tapped hole causing the
flattening of the bowed portion against the block 70
so that said bowed portion will exert pressure
against the head of the screw in order to resist
accidental loosening of the screw and said lugs
preventing turning of the segment and the con-
ductor relative to said block, and a contact carried 75
by the conductor for engaging a terminal of the
distributor head.

2. An ignition distributor rotor comprising a
non-connecting block of molded material having
a plane surface transverse to its axis a metal 80
insert in the block around which the material
of the block is molded, said insert having a
tapped hole and terminating flush with the plane
surface of the block, a leaf spring conductor
having a normally bowed portion located upon 85
the plane surface and insert, a metal segment
resting upon said normally bowed portion of the
leaf spring conductor, a screw passing through
holes in the segment and said bowed portion
and threadedly received by said tapped hole, the 90
threading of the screw into said tapped hole caus-
ing said normally bowed portion to become flat-
tened whereby said spring conductor causes pres-
sure to be exerted against the head of the screw
to resist accidental loosening thereof, at least 95
one lug provided by the block for engaging the
sides of the segment and spring conductor to re-
sist turning thereof relative to the block, and a
contact carried by the conductor for engaging
a terminal of the distributor head.

3. An ignition distributor rotor comprising a
non-conducting block of molded material having
a plane surface transverse to its axis a metal
insert in the block around which the material of
the block is molded, said insert having a tapped 105
hole and terminating flush with the plane sur-
face of the block, a leaf spring conductor having
a portion located upon the plane surface and
insert, a metal segment resting upon said por-
tion of the leaf spring conductor, a screw passing 110

through holes in the segment and said bowed portion and threadedly received by said tapped hole, the shank of said screw having, adjacent the screw head, an unthreaded tapered portion whose smallest diameter, which is nearest the threads of the screw, is slightly smaller than the hole of the segment through which the screw passes, and whose greatest diameter is slightly greater than said hole, the threading of the screw 5 into the insert causing said tapered shank to bind against the cylindrical wall defining the hole in the segment, at least one lug provided by the block for engaging the sides of the segment and spring conductor to resist turning thereof relative to the block, and a contact carried by the conductor for engaging a terminal of the distributor head.

4. A rotor for an ignition distributor comprising a block providing a tapped hole, a metal 20 segment supported by the block, a screw passing through a hole in the segment and threadedly engaging the tapped hole in the block, a conductor having a dish-out portion between the head of the screw and the block, the tightening of the 25 screw in said hole causing the dish-out portion to flatten so as to exert pressure against the head of the screw in order to resist accidental loosening of the screw, means carried by the block for engaging the segment and conductor 30 to prevent turning thereof relative to the block, and a contact carried by the conductor for engaging a terminal of the distributor head.

5. A rotor for an ignition distributor comprising in combination; a non-conducting block of 35 molded material having a pair of integral lugs; a metal insert in the block around which the

material is molded, said insert having a tapped hole located between said lugs; a leaf spring conductor having a normally bowed portion lying above the tapped hole; a segment resting upon the bowed portion of the conductor; a screw passing through holes in the segment and the bowed portion and threadedly received by the insert, the tightening of the screw causing the bowed portion to flatten to resist loosening of the screw and said lugs preventing turning of the segment and conductor relative to the block; and a contact carried by the conductor for engaging a terminal of the distributor head.
